UNITED STATES PATENT OFFICE.

HARRY WILLOUGHBY GRATTAN PLUNKETT, OF LONDON, ENGLAND.

SADDLE.

SPECIFICATION forming part of Letters Patent No. 606,281, dated June 28, 1898.

Application filed February 9, 1897. Serial No. 622,653. (No model.)

To all whom it may concern:

Be it known that I, HARRY WILLOUGHBY GRATTAN PLUNKETT, a subject of the Queen of England, residing at London, England, have invented certain new and useful Improvements in or Relating to Saddles, of which the following is a specification.

This invention relates to saddles suitable for, though not confined to, cycles, its principal object being the construction of a cushion and a saddle-frame adapted to become mutually engaged to constitute a saddle of light weight having a form which is hygienically advantageous as well as comfortable to the rider.

Another object is the construction of improved means for adjusting and securing the saddle in place upon the machine.

According to this invention the cushion may be formed as an inflatable or other body—say an inflatable tube—and the frame with its upper portion of twin wires or flanges, with a channel between them or as an equivalent channeled structure, with which the tube cushion or cover interlocks. For instance, there may be a bead or beads connected to the cushion or to the cover thereof by webs and engaged at each side by the twin wires of the frame. Whether the cushion as a whole be inflatable or not, it may have inflatable tubular beads which upon inflation will engage the tree in such a manner as to hold the cushion in place. The cushion is engaged with the frame by sliding the webs into the channel between the twin wires or the like.

The inflatable portion of the device can be provided with an air-valve through which air may be forced by an air-pump, or a fitted india-rubber air-ball having non-return valves may be used.

All the cushion lies approximately in one plane. The preferred shape in plan is one in which two tubular portions diverge from each other and from a point at the forward end of the saddle and are curved outward at the back to form loops.

In the accompanying drawings, Figure 1 is a side elevation of a saddle constructed according to this invention, comprising a portion of a seat-pillar and the device by which the saddle is adjusted and secured in place upon it. Fig. 2 is a plan of the saddle. Fig.

3 is a plan of the saddle-frame with the cushion removed. This figure is broken away. Fig. 4 is an elevation of the leading end of the saddle-frame. Fig. 5 is an elevation of the rear end of the saddle-frame, and Figs. 6, 7, and 8 are three views of the clip serving for the retention and adjustment of the saddle. Figs. 6 and 7 are elevations at right angles to each other, and Fig. 8 is a plan. Fig. 9 is a transverse section of the cushion on the line 9-9 of Fig. 2. Fig. 10 is a perspective view of one of the retainers B, hereinafter referred to. Fig. 11 is a perspective view of the bolt used to secure the saddle-clip to the supporting-post.

Like letters indicate like parts throughout the drawings.

A is the frame, which in the present example is constructed of stout wire as follows, it being understood that as the saddle and its appurtenances are symmetrical upon both sides of the longitudinal center line a description of the parts at one side of that center line will suffice also for those at the opposite sides:

A' is a wire looped at A² and A³, as seen clearly in side elevation in Fig. 1 and in plan in Fig. 3, so that the ends A⁴ and A⁵ may possess the elasticity necessary to easy riding. The end A⁴ is screw-threaded and supports a tubular retainer B, which is perforated longitudinally to receive the end A⁴ of the wire A', upon which it is secured by nuts A⁶ A⁷. The retainer is also perforated transversely, as at B', to receive the ends of twin wires hereinafter referred to. From the transverse perforations B' extend saw-cuts or slots B², so that when the nuts A⁶ A⁷ on the ends A⁴ of the wire A' are tightened up they cause the retainer B to grip the ends of the twin wires therein. The other end A⁵ of the wire A' is screw-threaded to receive nuts A⁸ A⁹, having between them two plates C C', which are slightly channeled upon their meeting faces to grip the aforesaid twin wires D D' and thus to hold the two halves or sections of the frame together at the forward end, at which the two halves may or may not be closer together than at the back.

D D' are twin wires which, starting from the plates C C', between which they are gripped, extend to the back of the saddle in parallel

lines and are curved in the manner indicated in Fig. 3 to form outwardly-extending loops, the back ends of the wires being gripped by the retainer B. Into the narrow channel left between these wires a portion of the cushion is introduced. To facilitate this introduction, the twin wires are so bent, as at D³, as to be slightly wider apart in proximity to plates C C' and retainer B than at other portions of their length.

To prevent the looped back portions of the saddle from being bent downward and to hold the two halves of the frame together, a stiffening-plate E, Fig. 5, is provided. It extends from side to side of the saddle in the manner indicated in Figs. 3 and 5 and is perforated to receive the ends A⁴ of the wires A', being retained in place thereon between the nuts A⁷ and retainers B.

20 The outer ends E' of the stiffening-plate E engage with and support the twin wires D D' and are cut away, as at E², so that there shall be no obstruction below the channel between the wires which would be likely to offer any hindrance to the insertion of the cushion.

25 F is the cushion. The example illustrated is tubular, comprising an inner inflatable air-tube F', closed at the ends except for a tubular connection F², with an air-ball-inflating device G, or the cushion may be fitted with an inflation-valve, as in a pneumatic tire, adapted to be engaged by the nozzle of a pump. This air-tube is inclosed in a casing F³, provided with a longitudinal bead F⁴, Fig. 9, extending along the whole length of the tubular cushion, with which it is connected by a narrow web F⁵. When the cushion is deflated, the bead F⁴ can readily be passed below the twin wires D D' in such a manner that the web F⁵ lies in the narrow channel between them and air-tube F' in its casing F³ above them, as shown in Fig. 9. The body of the cushion is a straight tube, becoming curved to the form of the frame G, having the web at both its ends first inserted between the twin wires and the bead below them at the open parts D³ near the plates C C', the tube being led around the curves of both sides of the frame, after which, upon inflation, it assumes the form illustrated in Figs. 1 and 2. From those portions of the cushion which occupy the leading end of the frame flaps F⁶ on the cover F³ may depend, as shown.

It is preferred that the saddle should have 55 in plan the shape indicated in the drawings, the forward end being formed of divergent portions F⁷, with a space F⁸ between them to avoid perineal pressure, and the back portion being constituted by loops or portions of approximately annular form, the forward sides F² of each annulus being, if desired, straight at right angles to the tubular portions F⁷, as shown.

The device by which the saddle is retained 65 and adjusted upon the seat-pillar will now be described.

H, Fig. 1, is a horizontal member of the seat-pillar.

J is a clip perforated at J', Fig. 6, to receive the portion H on the seat-pillar and cut 70 through, as at J², so that the sides of the clip may be brought together to grip the part H. From the body of this clip J wings J³ extend upward and forward, as shown, to support a transverse tube J⁴. Holes J⁵, Fig. 7, are provided in the wings J³ to receive a bolt K. The tube J⁴ receives a smaller bolt L, Fig. 1. About the bolt K the saddle can receive angular adjustment in the longitudinal central plane of the machine, the bolt L serving to 80 lock the saddle in the position in which it is thus adjusted.

M are plates lying against the outer faces of the wings J³ and provided with segmentally-slotted arms or extensions M'. These 85 plates are pivoted upon the bolt K, which passes through them and through the wings J³ and is provided with a head K', a nut K², and washer K³. The head K', washer K³, and plates M are channeled to grip the main 90 wires A' at each side of the frame, as shown in Fig. 6, the bolt K having a longitudinal central slot K⁴ sufficiently wide to enable it to be passed over both these wires A' when the bolt is inserted.

95 K⁵ is a small block placed in the end of the slot K⁴, near the nut, to prevent the sides of the bolt from being sprung toward each other when the nut is screwed home. Its edges may be screwed to fit the thread in the nut K², as best shown in Fig. 11. By rotating the plates M and bolt K about the axis of the latter the saddle can be tilted up or down as required to suit the rider's convenience. When it is thus tilted, the slotted arms M' move up and 100 down in proximity to the tube J⁴ of the clip J. The bolt L passes through the slots to the arms M', as well as through the clip J, and is tightened up to lock those arms to the socket in any of the positions to which they may 105 have moved during the adjustment of the saddle, as described. The bolt K not only serves as a pivot about which the saddle turns, but also when screwed up tight forces the sides of the socket inward, so that the 110 wires A' and the portion H of the seat-pillar are firmly gripped. By slackening the nut K² the grip of the head K' and washer K³ on the wires A' can be lessened to permit them to be adjusted endwise to alter the position 115 of the saddle longitudinally in relation to the clip. This longitudinal adjustment is additional to that which is obtainable by sliding the clip J along the part H of the seat-pillar.

This invention is not limited to the construction illustrated in the drawings, which is given merely by way of example, and may be varied without departure from this invention.

I claim—

1. In a saddle, a frame composed of parallel twin wires occupying the same horizontal

plane, and bent to conform to the outline of the saddle, and a cushion secured to the frame between said wires, substantially as set forth.

2. In a saddle, a frame comprising two like sections arranged side by side in the same horizontal plane, each consisting of parallel twin wires, and having a straight body portion and an outwardly-extending loop at the rear, and clamps for securing the sections together, substantially as set forth.

3. In a saddle, a frame comprising two like sections arranged side by side in the same horizontal plane, each consisting of parallel twin wires and having a straight body portion and an outwardly-extending loop at the rear, the body portions of the sections being separated to provide an intervening space and arranged to diverge toward the rear, a transverse stiffening-plate, and means for securing the sections and stiffening-plate together, substantially as set forth.

4. In a saddle, the combination with a frame comprising parallel twin wires arranged side by side in the same horizontal plane and bent to conform to the outline of the saddle, of an elongated cushion provided with a web having an edge bead and secured in place between said wires, substantially as described.

5. In a saddle, the combination with a frame comprising parallel twin wires arranged side by side in the same horizontal plane, and bent to conform to the outline of the saddle, of an inflatable tubular cushion likewise bent to conform to the outline of the saddle and secured in place between said wires, substantially as described.

6. In a saddle, the combination of the frame comprising two independent separated sections each consisting of parallel twin wires and having a straight body portion and an outwardly-extending loop at the rear, the said body portions being arranged to diverge toward the rear, means for securing the sections in position, and an elongated cushion secured to the frame between said wires and conforming to the outline of the frame, substantially as set forth.

7. In a saddle, the combination of the frame consisting of two independent sections each having an elongated body portion and an outwardly-extending loop at the rear, supporting-springs, means for securing the adjacent ends of the sections and springs together, a transverse stiffening-plate supported on said springs and engaging the loop portions of said sections, and a cushion, substantially as set forth.

8. In a saddle, the combination of the frame

consisting of two independent sections each composed of parallel twin wires and having a straight body portion and an outwardly-extending loop at the rear, two supporting-springs, means for securing the adjacent ends of said sections and springs together, a transverse stiffening-plate carried by said springs and engaging the under side of said sections, and an elongated cushion conforming to the outline of the frame and secured in place between said twin wires, substantially as set forth.

9. In a saddle, the combination of the wire frame terminating at the rear in outwardly-extending loops, the supporting-springs, and the retainers provided with openings at right angles to each other and adapted to secure the adjacent ends of said loops and springs together, substantially as set forth.

10. In a saddle, the combination of the frame consisting of two like sections, each composed of parallel twin wires and terminating at the rear in an outwardly-extending loop, the supporting-springs, the tubular retainers adapted to receive the rear ends of said springs and provided with transverse slotted openings for the ends of said loops, and means on said springs for tightening said retainers, substantially as set forth.

11. The combination with the saddle having substantially parallel supporting-springs, of a clip adapted to be secured to the saddle-post, a slotted bolt therefor through which said springs pass, segmentally-slotted plates pivoted on said bolt at the sides of the clip and adapted to clamp the springs thereto, and a second bolt passing through the clip and the segmental slots of said plates, substantially as and for the purpose described.

12. The combination with the saddle having substantially parallel supporting-springs, of a split clip adapted to be secured to the saddle-post, and provided with wings extending forwardly therefrom, a bolt passing through the body of the clip and slotted to receive said springs, a block fitted to said slot, plates pivoted at their inner ends on said bolt and having segmental slots at their outer ends, and a second bolt passing through said wings and segmental slots, substantially as and for the purpose described.

In testimony whereof I have hereto set my hand in the presence of the two subscribing witnesses.

HARRY WILLOUGHBY GRATTAN PLUNKETT,
Witnesses:

HAROLD WADE,
HARRY B. BRIDGE.
